UNITED STATES PATENT OFFICE.

WILLIAM B. ARNOLD, OF NORTH ABINGTON, MASSACHUSETTS.

PROCESS OF MAKING BOOTS AND SHOES.

1,085,002.

Specification of Letters Patent.

Patented Jan. 20, 1914.

Application filed May 31, 1913. Serial No. 771,068.

To all whom it may concern:

Be it known that I, WILLIAM B. ARNOLD, a citizen of the United States, residing in North Abington, in the county of Plymouth and Commonwealth of Massachusetts, have invented certain new and useful Improvements in Processes of Making Boots and Shoes, of which the following is a specification.

10 My invention relates to a new and improved process for making boots and shoes. In the drawings where the same characters are used to indicate the same parts wherever they occur, Figure 1 in top plan view shows what I term a middle sole employed in my process. Fig. 2 in top plan view shows a piece of welt. Fig. 3 in top plan view shows the middle sole with a welt temporarily secured in position thereon by cement or otherwise, and extending around the edge of the middle sole from the heel of the inside to the heel of the outside. Fig. 4 is a view similar to Fig. 3 showing the welt extending all the way around the edge of the middle sole. Fig. 5 is a cross sectional view, showing the needle in the position occupied in sewing the welt to the insole and further showing the use of the edge of the middle sole as a guide for the needle and a positioner of the seam made by the needle in the welt and insole, the needle and thread appearing at the right and the thread of the seam or other fastening means appearing at the left. Fig. 6 is a cross sectional view, a filler appearing between the middle sole and insole. Fig. 7 is a view showing the outsole applied and the needle in position to stitch the outsole to the welt. Fig. 8 is a view showing the outsole applied to 40 the middle sole and the needle in position to stitch the outsole to the welt.

While I have shown a shoe in illustrating my invention, I wish it to be understood as not limitating myself to a shoe, since my invention embraces boots, shoes, and all footwear wherein a welt, so called, is employed in its manufacture. I therefore desire to be understood as embracing footwear generally, wherever the word "shoe" is employed. I have not illustrated the forming or shaping of the upper or the insole or the shaping and attaching of the upper to the insole, since these steps constitute no part of my invention, and may be carried out by 55 any well-known or preferred process. My improved process, or the "Arnold" process,

so-called, is principally concerned with the steps following the securing of the upper to the insole.

1 represents what I term a middle sole, 60 which may be made of leather or any other suitable material. This middle sole while it corresponds to the general lines of the insole, is made sufficiently smaller than the insole to permit the passage of a needle by the edge of the middle sole and through the insole for the proper location of the seam in the upper and the insole. This difference in the size of the middle sole should exist for so much of the edge of the middle sole as is 65 to be used for a guide for the sewing needle.

2 represents a welt. This may be of any well known or desired construction. The form of the welt is that illustrated in United States Patent No. 674,831 granted to me on 70 the 21st day of May 1901.

In practising my process the welt is placed by hand or machine upon the middle sole and temporarily secured by cement or otherwise to the middle sole as shown in Figs. 3 80 and 4, the welt projecting beyond the middle sole the distance it is desired to have the outsole project beyond the seam joining the welt to the insole. The middle sole and its attached welt is then cemented or 85 otherwise temporarily secured in proper position to the bottom of the shoe, the edge of the middle sole being placed on the bottom of the shoe where it is desired to have the inseam made. The welt is then stitched 90 or otherwise secured by any desired means to the insole.

While I have employed the word "seam" and "needle" I have employed these terms for the purpose of illustration. My invention embraces and I wish it to be understood as asserting that it embraces the described steps, irrespective of the form of bonding means employed to hold the welt to the insole and irrespective of the instrumentalities for placing said bonding means in the shoe.

In securing the welt to the insole, the needle 3 or other bond placing instrument is guided by the edge of the middle sole, thus 105 locating the seam or other bonding means at a definite and predetermined distance from the outer edge of the welt, and the outer edge of the insole by the act of and at the time of placing the bonding means. If the 110 usual means are employed for securing the insole to the welt, the middle sole serves as a

positive and safe guide for the needle or other bonding tool.

Under my process, after the welt is secured to the insole, the middle sole may be removed, and a filler 4 applied in the usual way as in Figs. 6 and 7, or a filler may be applied to the middle sole as in Fig. 8, in which case the middle sole need not be removed. Where it is desired to follow my process, and not remove the middle sole, the latter may be made of any desired material. Since my patented welt is only $\frac{1}{2}$ as thick on the inside of the inseam as on the outside of the inseam, only a little skiving of the edge of the middle sole would be necessary to make the top surface of the middle sole flush with the top surface of the welt when it is desired to use the middle sole as a permanent part of the shoe. The middle sole may serve as a welt holder and seam positioner or, as already stated, it may in addition be used as a permanent part of the shoe. The use and the non use of a filler is of course optional, as is the use of the middle sole as a permanent part of the shoe.

In Figs. 6 and 8 the middle sole 1 appears for clearness of illustration as it would appear if the middle sole were to be removed and not made a permanent part of the shoe. When it is desired to retain the middle sole as a permanent part of the shoe, as in Figs. 6 and 8, the edge of the middle sole should be pared or skived flush with the welt 2 or a marginal filler employed on the welt so that the outsole will rest on the middle sole and welt or marginal filler on the welt before stitching the outsole to the welt as the outsole rests on the filler and welt in Fig. 7.

While I have used the word "middle sole" in referring to the part 1, I do not wish to be understood as limiting my inven-

tion to a middle sole, since this part may be removed or may be used as a permanent part of the shoe as desired. Wherever I employ the word "middle sole" I desire to be understood as embracing any sole-shaped device capable of holding a welt in position for attaching the welt to the insole and for guiding the needle or other bonding means and positioning the inseam.

I believe myself to be the first to use a sole-shaped device as a welt holder and inseam positioner, whether said sole shaped device be removed after the welt is attached to the insole or be used as a permanent part of the shoe and I desire to claim the same in the broadest possible legal manner.

I claim:

1. The process of making shoes which consists in applying a welt to a middle sole, applying said middle sole and its welt to the bottom of a lasted or otherwise shaped upper and insole, securing the welt to the insole by an instrumentality guided by the edge of the middle sole and completing the shoe in any desired way.

2. The process of making shoes which consists in applying a welt to a middle sole at the marginal portion thereof, applying said middle sole and its welt to the bottom of a lasted or otherwise shaped upper and insole, securing the welt to the insole by an instrumentality guided by the edge of the middle sole, and completing the shoe in any desired way.

In testimony whereof I have hereunto affixed my signature in the presence of two witnesses.

WILLIAM B. ARNOLD.
